TELEGRAPHIE M. B. H., OF BERLIN, GERMANY

RADIO RECEIVING SYSTEM

Application filed February 11, 1926, Serial No. 87,508, and in Germany February 14, 1925.

The present invention relates to a receiving arrangement for transmitted high frequency energy.

The object of my invention is to provide an arrangement whereby disturbances, especially atmospheric disturbances, may be minimized.

Other objects and advantages of my invention will appear more fully as hereinafter set forth in connection with the accompanying drawings, in which

The single figure illustrates diagrammatically a preferred embodiment of my invention.

In the usual radio receiving systems which generally comprise a number of electron tubes for the purpose of amplification and rectification, the receiving aerial and the lead by which the incoming high frequency oscillations are fed to the receiver are connected with the apparatus so that all current and potential variations which arise in the aerial cause corresponding actions in the receiving apparatus. As a consequence disturbances, especially "strays" which consist of the excitation of natural oscillations in the antenna system act upon the receiving apparatus.

By the arrangement herein contemplated, the time is to be shortened during which the receiver is liable and subject to disturbing actions. Indeed, the receiving outfit is capable of reception only so long as energy is being radiated from the transmitting station. While heretofore for the feeding of tube receivers, it has been customary practice to use a direct current source or else a low frequency alternating current source, in the present invention, the anode potential is furnished by a high frequency current of the frequency of the transmitter to be received from. The high frequency alternating current by which the anode potential is produced in the receiver must be in synchronism and in phase with the desired incoming signal oscillations. If the anode or plate potential is not in phase with the oscillations supplied to the grid of the tube, but is on the contrary displaced by an angle of 180 degrees, then, with a correct adjustment of the working point of the tube, no current will be able to flow in the plate

circuit, so that the indicator will be unable to respond. In accordance with the method contemplated by this invention, an electron tube or an electron tube arrangement is used as the generator for the high frequency current which is to be employed for the feeding of a second electron tube arrangement, which latter constitutes the receiving outfit proper. The tube which is to supply the plate potential, for instance, by means of retroactive coupling, can be adjusted so that it is just below the point of oscillations,—the addition of the desired incoming energy coming from the remote transmitter supplying sufficient energy for the purpose of maintaining the tube in a state of oscillation. If the amount of energy received from the remote transmitting station is insufficient to produce oscillation for retroactive coupling, then the coupling between the two tubes and the coupling of one tube with the aerial must be made sufficiently close in order that the oscillations of the local tube generator will be produced.

If shock excitations should be produced, by atmospheric discharges, for example, disturbances will be noted in the indicating means due to these cophasal excitations of the local oscillator. In order that this may be prevented from occurring the aerial may be untuned with relation to the oscillations to be received so that the natural period of the aerial possesses another frequency than the frequency to be received and by the aid of special well-known means (phase shifters or advancers) the coupling of the two tube generators with the aerial would be so set that it is solely for the oscillation desired to be received that the proper phase condition or relation between the grid potential and the receiver of the high frequency plate potential produced by the local generator exists. However, a more preferable scheme is to use two separate aerials for the two tube arrangements and to detune these aerials with reference to one another, for example, symmetrically above and below the frequency to be received.

An arrangement according to the invention is shown in the drawing in which A_1 is a receiving aerial coupled through the me-

dium of coils 1, 2 to the triode R_1 . Triode R_1 as will be noted is regeneratively coupled as is well known through the medium of coil 3 in the output circuit of R_1 . 10 represents the usual receiving telephone. A second aerial system A_2 is shown connected to a triode R_2 through coils 8, 6. Triode R_2 is also regeneratively connected by means of coil 7 and is so arranged and adjusted that oscillations are generated in said triode. For purposes of energizing the plate circuit of triode R_2 a direct current battery 9 is provided. It will be noted that no plate battery appears for the output circuit of tube R_1 . 15 However, for purposes of supplying the plate of tube R_1 with the proper potential a transformer T comprising coils 4 and 5 is provided and adapted to feed the high frequency potential of the generator tube R_2 to the plate of tube R_1 .

The advantage of the system directed above over other arrangements having the aim and purpose of compensation of oscillations of a different frequency, is that by 25 the utilization of phase differences in one tube the energy transfer of a receiver for undesirable oscillations is interrupted.

By the suitable detuning of the aerial and tuning of the receiving circuits it is feasible to render the whole receiving arrangement operative solely for the frequency of the transmitter to be received, while for all other frequencies, but most particularly for the shock excited natural periods of the 35 aerial, the operative phase relations between the oscillations of the distant transmitter and the high frequency plate potential locally generated, which are pre-requisites for reception, are not established.

40 For the elimination of the shock excited oscillations it is further suitable to choose the time constants of the oscillatory systems of the total arrangement as differently as possible, for by this means the difference in 45 the action of the shock excited oscillations and the impressed oscillations is further promoted; in other words, by choosing the time constants of the circuit incorporating triode R_2 differently from the time constants of the 50 circuit incorporating triode R_1 which may be done by simply proportioning the elements composing the circuits, it will be seen that upon the two circuits being excited by the 55 same shock disturbances one circuit would lag behind the other due to the difference in time constants between the two and in fact the dying down of the oscillations of the circuits would be different.

60 It will be understood that the details of the method and arrangement herein set forth may be varied and that the general principles herein disclosed may be embodied in other organizations as fairly fall within the scope 65 of the appended claims.

What I claim is:

1. In a high frequency signalling system, a circuit comprising an electron tube arrangement adapted to oscillate under the influence of incoming oscillations, a second electron tube circuit having a plate circuit coupled to said first circuit and means comprising said first mentioned electron tube circuit for energizing the plate circuit of the second electron tube circuit solely from the high frequency oscillations generated by said first circuit when said first circuit is oscillating under the influence of oscillations remotely excited. 70 75

2. A receiving arrangement comprising a tuned input oscillation circuit adapted to oscillate when a frequency to which the circuit is tuned is impressed upon the aerial, a second tuned input discharge tube circuit having a plate circuit, said oscillation circuit being coupled to the plate circuit of said discharge tube circuit, means comprising said oscillation circuit for energizing the plate circuit of said discharge tube, and an indicating device associated with the output circuit of said discharge tube and adapted to respond to desired signals impressed on the second input circuit. 80 85 90

3. A receiving arrangement comprising a pair of aerials, a tuned oscillation circuit coupled with one of the aerials and adapted to oscillate when a frequency to which the circuit is tuned is impressed upon the aerial, a second tuned discharge tube circuit having a plate circuit, said last named discharge tube circuit being coupled to the other aerial, 95 100 said oscillation circuit being coupled to the plate circuit of said second named discharge tube, said oscillation circuit being adapted to energize the plate circuit of said tube, and an indicating device connected in the plate circuit of said tube adapted to respond to desired signals impressed on the input circuit of said tube. 105

4. In a signal receiving system a pair of aerials detuned with respect to one another, 110 separate electron tube circuits having grid and plate circuits, said electron tube circuits being connected to each of said aerials, one thereof being so adjusted that oscillations will be generated therein under the influence 115 of incoming signals and means comprising said oscillations for energizing the plate circuit of said other tube circuit. 115

5. In a radio system a pair of aerials tuned 120 respectively symmetrically above and below the frequency of incoming energy, an oscillation generator circuit coupled to one of said aerials and an electron tube circuit, having grid and plate circuits, coupled to said other aerial, means comprising incoming energy for setting said generator into operation and means for impressing the resulting oscillations in the plate circuit of said electron tube circuit. 125
